UNITED STATES PATENT OFFICE

EDWARD H. SCHANE, OF CLEVELAND, OHIO, ASSIGNOR TO THE FANNER MANUFACTURING COMPANY, OF CLEVELAND, OHIO, A CORPORATION OF OHIO

CHAMFERING ATTACHMENT FOR CHAPLET-MAKING MACHINES

Application filed October 22, 1926. Serial No. 143,348.

This invention relates to a chamfering attachment for chaplet making machines and has for its object to embody in such a machine a device by means of which the free ends of the chaplet stems are automatically beveled or chamfered prior to the discharge of the finished chaplets from the machine.

In the chaplet making machines ordinarily employed the stems of the chaplets are successively cut from a continuous length of wire and are riveted at regularly spaced points to a strip of sheet metal which strip is severed between successive stems. The cutting of the wire forming the stems and the riveting of the stems form a slight burr upon the outer ends of the chaplet stems, and this burr interferes with the proper fit of the stems into the apertures of the pattern parts with which they are used.

20 The present invention provides automatic means forming a part of the chaplet machine by which the burrs are removed from each stem and a slight taper is formed on the ends of the stems to insure ease of insertion and 25 accurate fit in the openings of a pattern member.

The following description and accompanying drawings set forth in detail certain means embodying invention, the disclosed means, 30 however, constituting but one of the various mechanical cases in which the principle of the invention may be employed.

Reference should be had to the accompanying drawing forming a part of this specification in which:

Fig. 1 is a vertical longitudinal section of the chaplet forming machine to which the present invention is applied.

Fig. 2 is a front elevation of the machine 40 shown in Fig. 1.

Fig. 3 is a sectional detail view showing the chamfering tool in engagement with the stem of a chaplet.

Fig. 4 shows in side elevation, a portion 45 of the strip with a stem attached thereto as it appears before the chamfering operation.

Fig. 5 is a side elevation of a finished chaplet as it is delivered from the machine.

Referring to the accompanying drawings 50 the chaplet making machine is provided with

a bed 1 and standards 2 extending upwardly from the bed at opposite sides thereof and having an eccentric shaft 3 journaled at its opposite ends therein adjacent the upper ends thereof. Shaft 3 is provided with an eccentric 55 4 which supports a reciprocating head 5 which is guided for movement vertically between the standards 2. The head 5 carries on its under side a punch 6 and a riveting die 7 and cooperating with the head 5 there is a block 8 secured upon the bed and adjacent the rear end thereof, the block 8 having an aperture 9 in alignment with the punch 6 and in advance of aperture 10 through which wire may be fed. Adjacent the forward edge 60 of the block 8 there is mounted a lower riveting die 11 which co-operates with the die 7 carried by the head 5 and adjacent the upper end of the aperture 10 there is a wire cutter 12 by means of which the wire is cut to the proper 65 length for forming the chaplet stems. A sheet metal strip is fed forwardly over the block 8 and die 12 by means of a reciprocating feed arm 14 which is provided with a head 15 upon which the strip rests and with a pivoted gripper 16 by means of which the strip is gripped and held against sliding on the head 15 during the forward movement thereof. The operation of the feeder alternates with the stroke of the head 5 so that the strip 13 is 70 stationary during engagement of the punch 6 and die 7 therewith. The stroke of the 75 feeder arm 14 is exactly equal to the distance between the apertures 9 and 10 and the distance between the aperture 10 and the center 80 of the die 7 is such that upon each stroke of the feeder arm the strip is advanced to position an aperture formed by the punch 6 in registry with the aperture 10 to permit the wire to be fed up through the strip and to 85 90 position a stem between the riveting dies. A suitable feed is provided for the wire to cause the wire to be advanced through the strip the length of a chaplet stem and the cutter 12 is so timed as to operate immediately after 95 the feed of the wire is completed. Upon the stroke of the head 5 an aperture is formed in the strip 13 and a piece of wire is fed through an adjacent aperture and a stem is riveted to the strip by means of the co-acting 100

dies 7 and 12. The chaplet making machine so far described is old and well known and the actuating mechanism for the various feeds has not been shown, the feed devices, however, are timed in their operation with respect to the operation of the head 5, being operated by suitable cams driven from the eccentric shaft, the eccentric shaft being provided with a bevel gear 17 at one end which 10 meshes with a bevel gear 18 upon the upper end of a vertical shaft 19 which extends downwardly below the bed and drives the various cams for operating the strip feeder, the wire feeder and the strip cutter.

15 The severing of the wire by the cutter 12 and the operation of the dies 7 and 11 has a tendency to form a slight burr upon the upper ends of the stems 20 as indicated at 21 in Fig. 4. The purpose of the present invention is to provide in connection with the chaplet making machine, such as above described, a device by means of which the burr at the upper end of the stem is removed and the stem is slightly pointed or tapered to 25 facilitate its insertion into the openings of a pattern member.

In chaplet machines heretofore employed the sheet metal strip has been severed by means of a cutter attached directly to the 30 reciprocating die head. In the present invention, however, the cutter is spaced forwardly from the reciprocating head 5 and is separately mounted. A block 23 is secured to the bed forwardly of the die 12 and this 35 block has attached to the forward edge thereof a stationary cutter blade 24. At the forward end of the block 23 there is formed a vertical guide way 25 in which is mounted a head 26 which carries the cutter bar 27 which 40 co-operates with the fixed bar 24 to shear the strip 13 midway between the attached stems 21. The head 26 is suspended by means of links 28 from a transverse shaft 29 supported in brackets 30 carried by the standards 2. 45 The links 28 have elongated slots 31 at their upper ends through which the shaft 29 extends and are provided with inwardly projecting pins 32 which engage with the cam slots 33 formed on the outer faces of a disk 34 fixed to one end of the shaft and a gear 35 fixed to the opposite end of the shaft. Rotation of the shaft 29 causes the link 28 and head 26 to be raised and lowered during each 50 revolution of the shaft and means is provided for so driving the shaft 29 as to properly time the operation of the cutter head. 55 To this end the gear 35 meshes with a small gear 36 fixed to a transverse drive shaft 37 and the gear 36 also meshes with a large gear 60 38 fixed to the eccentric shaft 3, the gears 35 and 38 are preferably of the same pitch diameter so that the rotation of the shaft 29 is at the same speed as the rotation of the shaft 3 and the cam slots 33 are so disposed 65 with respect to the eccentric disk 4 that a

chaplet is severed from the strip during each interval between the feed movements of the strip or at approximately the same time that the head 5 is in engaging position with respect to the strip.

70 The chamfering device which is interposed between the reciprocating head 5 and the cutter head 26 will now be described. A gear housing 39 is rigidly mounted on a cross bar 40 extending between opposite sides of the frame directly above the block 23 and journaled in this housing is a horizontal shaft 41 to which is fixed a helical gear 42 which meshes with a horizontally disposed helical gear 43 rotatably supported in the housing and splined to a vertical shaft 44 which is mounted to slide up and down through the gear 43. The shaft 44 carries at its lower end a chamfering head 45 which is provided with a conical recess 46 adapted to receive the upper end of a chaplet stem and having cutting teeth 47 therein by means of which the stems are cut to a slight taper, as best shown in Fig. 3. Rotation is imparted to the shaft 34 by means of the shaft 41 and gears 42 and 43, the shaft 41 being driven by means of a pulley 48 at its outer end and a belt 49 which runs over the pulley 48 and over a large pulley 50 fixed to the drive shaft 37.

75 In order to enable the chamfering tool to operate successively upon the chaplet stems means is provided for automatically lowering the shaft 44 during intervals between successive feed movements of the strip 13 and for elevating the shaft 44 and head 45 to permit feed movements of the strip. The upper end 52 of the shaft 44 is threaded and carries nuts 53 and 54 which clamp a sleeve 55 having upper and lower flanges 56 which receive between them the forked end 57 of a lever 58 which is secured to a rock shaft 59 journaled in the lower portions of the brackets 30. The arm 58 is secured to the central portion of the shaft 59 and has integral therewith an upwardly extending arm 60 which carries a roller 61 at its upper end which bears upon the cam 62 fixed to the shaft 29 midway between the brackets 30. The roller 61 is held in engagement with the cam 62 by means of a suitable spring 63 acting on the rock shaft 59. Cam 62 is so disposed with respect to the cam slots 33 in the disk 34 and gear 35 fixed to the shaft 29 that the chamfering tool is lowered into engagement with a chaplet stem while the strip 13 is stationary and is lifted out of engagement prior to the feed movement of the strip.

80 Having thus described my invention, what I claim is:

1. The combination in a chaplet making machine of a bed, means for intermittently feeding a sheet metal strip along the bed, a reciprocating riveting head movable toward and from the bed for attaching wire stems to the strip at regularly spaced intervals

- along the length thereof, a reciprocating cutter spaced from the riveting head and operating in timed relation with respect thereto for severing the strip between successive stems, a rotary chamfering tool movably mounted between the riveting head and cutter, means operating in timed relation with respect to the movements of the head and cutter for shifting said tool into engagement with a stem, and means for driving said tool.
2. The combination in a chaplet making machine of a bed, means for intermittently feeding a sheet metal strip along the bed, a reciprocating riveting head movable toward and from the bed for attaching wire stems to the strip at regularly spaced intervals along the length thereof, a reciprocating cutter spaced from the riveting head and operating in timed relation with respect thereto for severing the strip between successive stems, a longitudinally movable shaft mounted between the head and cutter for movement toward and from the bed, a chamfering tool carried by said shaft, means for driving said shaft, and means operating in timed relation to the movements of said head and cutter for shifting said shaft.
3. The combination in a chaplet making machine of a bed, means for intermittently feeding a sheet metal strip along the bed, a reciprocable riveting head mounted for movement toward and from the bed, a shaft having an eccentric for actuating said head, a drive shaft geared to said eccentric shaft, a reciprocable cutter spaced from said head and movable toward and from the bed, a chamfering tool mounted between the cutter and head for movement toward and from the bed, and means driven from said drive shaft for actuating said cutter and chamfering tool.
4. The combination in a chaplet making machine of a bed, means for intermittently feeding a sheet metal strip along the bed, a reciprocable riveting head mounted for movement toward and from the bed, a shaft having an eccentric for actuating said head, a drive shaft geared to said eccentric shaft, a reciprocable cutter spaced from said head and movable toward and from the bed, a rotary chamfering tool between said head and cutter mounted for movement toward and from the bed, means for driving said chamfering tool, and means driven from said drive shaft for actuating said cutter and for shifting said chamfering tool.
5. The combination in a chaplet machine of means for intermittently feeding a sheet metal strip, means for riveting wire stems at regularly spaced intervals along the strip, a cutter for severing the strip between attached stems, a chamfering device comprising a shaft movable lengthwise toward and from said strip, a chamfering tool carried by said shaft at the end thereof and having a conical recess adapted to receive the end of a stem and provided with cutting teeth, means for driving said shaft and means operating in timed relation to the feeding means for moving said shaft, to engage said tool with successive stems.
6. In a chaplet making machine, means for feeding stock to provide a head for said chaplet, means for piercing said head to provide an opening therein, means for feeding a continuous wire through said opening, means for severing said wire to provide a stem, means for riveting said stem to said head, and means for chamfering the end of said stem.
7. In a chaplet making machine, means for intermittently feeding a sheet metal strip, means for piercing said strip to provide openings therein, means for feeding a continuous wire through said openings, means for severing said wire to provide stems, means for riveting said stems to said strip, means for chamfering said stems, and means for severing said strip between adjacent stems.
- In testimony whereof, I hereunto affix my signature.
- EDWARD H. SCHANE.
